(57) **CLAIM**

The ornamental design for an electric motorized wagon, as shown and described.

DESCRIPTION

FIG. 1 is a rear perspective view of an electric motorized wagon showing our new design.

FIG. 2 is a front perspective view thereof.

FIG. 3 is a front elevational view thereof.

FIG. 4 is a rear elevational view thereof.

FIG. 5 is a right side elevational view thereof.

FIG. 6 is a left side elevational view thereof.

FIG. 7 is a top plan view thereof; and,

FIG. 8 is a bottom plan view thereof.

Broken lines as shown in the attached drawings show the features of the electric motorized wagon that form no part of the claimed design.

1 Claim, 8 Drawing Sheets
